UNITED STATES PATENT OFFICE.

ELIHU THOMSON, OF NEW BRITAIN, CONNECTICUT, ASSIGNOR TO THE AMERICAN ELECTRIC COMPANY, OF SAME PLACE.

DYNAMO-ELECTRIC MACHINE.

SPECIFICATION forming part of Letters Patent No. 269,605, dated December 26, 1882.

Application filed September 18, 1882. (No model.)

To all whom it may concern:

Be it known that I, ELIHU THOMSON, a citizen of the United States, and a resident of New Britain, in the county of Hartford and State of Connecticut, have invented certain new and useful Improvements in Dynamo-Electric Machines, of which the following is a specification.

The object of my invention is to prevent the wear and destruction of the commutators of dynamo-electric machines, caused by the spark or flash which occurs when the brushes or collectors of the machine pass from one commutator plate or segment to a succeeding one.

15 My invention consists in the employment of condenser-surfaces connected to the coil-terminals of the armature, as hereinafter described.

In the accompanying drawings I have shown 20 my invention as applied to what is known as a "three-coil armature machine," of the general type shown in Letters Patent of the United States No. 223,557, dated January 13, 1880, and No. 233,047, October 5, 1880; but in showing 25 the invention in connection with this class of machines I do not wish to be understood as limiting myself to such an application thereof, and the same arrangement of condenser-surfaces and connections may be used with 30 other kinds of dynamo-electric or magneto-electric machines, having a greater or less number of armature-coils and commutator-segments, or even with electric motors, the terminals of the coils that are connected to the 35 commutator plates or segments of said motors being placed in electric connection with separate condenser surfaces or plates, as herein set forth with reference to dynamo-electric machines.

40 In the accompanying drawings, Figure 1 is a vertical longitudinal section of an armature-carrier or structure for a three-coil spherical armature of the same general form as is described in Patent No. 233,047. This figure 45 shows my condenser attachment N in place upon the armature-shaft. Fig. 2 is an end view of the armature. Fig. 3 is a diagram view, illustrating the manner in which the armature-coils, commutator, and condenser are connected to one another. Fig. 4 illustrates a modified arrangement, in which a supplemental

commutator is used in connection with the regular commutator and condenser. Fig. 5 shows a construction whereby the condenser may be stationary while the armature-coils and commutator revolve.

55 Referring to Fig. 1, G G indicate circular plates or frames of iron, which are suitably mounted upon and secured to the shaft S of the machine. Extending from one to the other 60 of these plates is a series of separate bridges of any suitable material, two of which are shown at I I, and which serve to support iron wire wound on the exterior, as shown, so as to give to the whole the form of an oblate spheroid. Projecting pins P P are inserted at suitable intervals as guides in winding the insulated wire, which latter, when the armature is 65 complete, gives to said armature the form shown by dotted lines. At each end there surrounds the shaft S a series of strips, R R, preferably of an insulating material, leaving flutings or grooves around the shaft. These flutings or grooves might be formed in the shaft itself in the process of manufacture, the strips 70 or ribs R R being integral with the shaft. This construction of armature-carrier is contained 75 in prior applications for patent filed by me, and no special claim is herein made to it.

80 N represents a box supported on the shaft in any suitable manner, and containing a condenser with connections t t t from its inclosed plates, to which connections the armature-coils are joined in a manner that will be presently described.

85 In Fig. 2 the armature-coils B' B² B³ are seen to lie around the ribs R in such manner as to leave open air-spaces around the shaft. When the armature is revolved air enters at 90 these points, and is ejected through the coils, where they overlap, by numerous small air-channels that invariably exist, and greatly promotes the cooling of the armature. There are twelve projections P P, &c., dividing and guiding the coils.

95 Fig. 3 shows the arrangement of connections of armature-coils, commutator, and condenser. The parts are shown separated for clearness. The armature-coils B' B² B³ are joined at J, and their other terminals are, as usual in machines constructed according to the plans patented to me, connected respectively to the seg-

ments of a three-segment commutator, $K' K^2 K^3$, mounted on the shaft S . These segments are also connected, in the manner shown, to surfaces $m' m^2 m^3$, of tin-foil or other suitable material, having the usual interposed insulator, and forming altogether a condenser, N , mounted by preference upon the armature-shaft, and having three independent sets of condenser-plates, (built up symmetrically in the well-known way,) instead of the two sets ordinarily employed, the combined plates of each set, m' , or m^2 , or m^3 , representing about ten square feet (more or less) of active surface. The size of the condenser-surface will, however, vary with the size of the machine and the nature and strength of the spark which it is desired to suppress. With the arrangement of condensing-surfaces described the spark at the commutator may be made to almost entirely disappear, in virtue of the condenser-surfaces being always ready to receive and condense or absorb any residuum of current which might make its appearance at the slots in the commutator when passing the collecting-brushes.

In Fig. 4 a still more complete device employing the same parts is shown. The coils $B' B^2 B^3$ are connected as before, at one end, J , and separately to the three segments $K' K^2 K^3$ of the commutator. The condenser in this case has six independent foil surfaces, (instead of the three foil surfaces or sets of foil surfaces shown in Fig. 3,) insulated and used in three pairs—that is, it is virtually three condensers, each having two opposed foils or plates. Commutator-segment K' is connected to one foil or surface of a condenser, the other or opposed foil or surface of which is connected to a corresponding segment, L' , in a secondary commutator. Again, K^2 is connected to one surface of another condenser, the opposed surface to which is connected to L^2 . In like manner K^3 of the primary commutator and L^3 of the secondary commutator are connected to the two poles or opposed surface of the third condenser. There is, under these conditions, no metallic connection from K' to L' , K^2 to L^2 , or K^3 to L^3 , but they are, as it were, inductively connected on account of their condenser-foils being respectively opposed. Whatever electrical impulse appears in K' , K^2 , or K^3 is reflected also in $L' L^2 L^3$, respectively. The commutator-brushes applied to $K' K^2 K^3$ are two connected pairs, $V' W'$ and $V^2 W^2$, respectively, which occupy different angular positions, as shown. A pair of brushes, U' and U^2 , bear on the secondary commutator $L' L^2 L^3$ at opposite points, and are singly connected to the other commutator-brushes, U' to V' and W' , and U^2 to V^2 and W^2 . The several brushes are so set that the slots between the segments of the commutator $K' K^2 K^3$ shall slightly precede those in $L' L^2 L^3$ when leaving the tips of the brushes. This condition is shown in the figure where the slot between K^2 and K^3 has just passed the brush V' , while that between the corresponding segments, L^2 and L^3 , is at the

same moment just under the brush U' . Under these circumstances very little spark is produced at the slots in the commutator-segments $K' K^2 K^3$; but the current that would produce it goes to the condenser and is absorbed, while a momentary efflux of current from the secondary commutator takes place. These currents are joined together and carried through the field-magnet coils $C C$ and light or other resistance a .

In Fig. 3 the condenser N is shown as revolving with the shaft; but this is not essential. Fig. 5 shows it stationary. In this case three rings, $r' r^2 r^3$, mounted on the shaft and insulated from one another, are connected respectively with the segments $K' K^2 K^3$ of the commutator. Upon the rings $r' r^2 r^3$ bear brushes $y' y^2 y^3$, separately connected to the condenser-foils. The action of this arrangement is precisely the same as that of Fig. 3.

My invention may be carried into effect by the employment of any desired construction of condenser. Said condenser may be mounted and connected to the armature coil-terminals in other ways or by other means besides those herein shown without departing from the invention.

What I claim as my invention is—

1. The combination, with a dynamo-electric machine, of a condenser the separate foils or surfaces of which are continuously connected to separate segments of the commutator.
2. The combination, with a dynamo-electric machine, of a condenser mounted upon the armature-shaft and connected to the commutator-segments in the manner described.
3. As a spark-absorber in a dynamo-electric machine, a set of condensing-surfaces in continuous connection with terminals of the armature-coils, and commutator-segments connected to said terminals, respectively.
4. The combination, in a dynamo-electric machine, of an armature having three coils united in a common joint or electrical connection, J , a three-segment commutator, to the segments of which the free ends of the coils are respectively connected, and a condenser connected to the segments in the manner described.
5. The combination, with a dynamo-electric machine, of a condenser consisting of a number of pairs or sets of condensing surfaces or plates, connected in the manner described to the separate segments of the primary or main commutator and to the segments of a secondary or supplemental commutator.
6. The combination, with a three-coil armature, of a primary or main three-segment commutator, a secondary three-segment commutator, a pair of condensing surfaces or plates inductively uniting the corresponding segments of the two commutators, and electrical connections from the brushes of the primary to the brushes of the secondary commutator.
7. In a dynamo-electric machine, the combination, substantially as described, of a primary and a secondary commutator inductively

united through the plates or foils of a condenser, and arranged with relation to one another so that their segments shall leave their brushes—the segments of one commutator

5 slightly in advance of those of the other.

8. The combination, with a dynamo-electric machine, of a condenser the separate foils or surfaces of which are in continuous electrical connection with the separate terminals of the

10 armature, as and for the purpose described.

Signed at New Britain, in the county of Hartford and State of Connecticut, this 12th day of September, A. D. 1882.

ELIHU THOMSON.
